UNITED STATES PATENT OFFICE.

DAVID ALBERT VICTOR RIST, OF OULTON BROAD, NORFOLK, ENGLAND.

METHOD OF AND MEANS FOR MANUFACTURING EMBOSSED OR INTAGLIO NAME
AND NUMBER PLATES.

Application filed April 12, 1927, Serial No. 183,222, and in Great Britain December 14, 1926.

This invention relates to the manufacture by a stamping operation of embossed or intaglio metal plates, which have an appearance similar to that produced by an ordinary engraving or milling machine.

One object of the present invention is to provide an improved method of and means for manufacturing embossed or intaglio metal plates whereby the device to be produced can be raised above the surface of the metal plate without danger of entirely severing or unduly weakening the connection between the raised portion and the plate.

15 A further object of the invention is to ensure that, when very high relief for example is not required, the metal forming the connection between the raised portion and the plate shall be consolidated and strengthened by compression. It is also contemplated to produce a raised device on a metal plate such that the sides of the device are substantially vertical relatively to the plate but are merged into the raised surface of

20 the said device at the upper edges thereof. According to this invention the male portion of the die is so dimensioned relatively to the female portion or counterpart that, upon the application of sufficient pressure, the male portion of the die will push the metal bodily with a semi-shearing action into the counterpart whereby the device, either embossed or intaglio, will be formed with vertical sides.

25 In this respect my invention differs from previous methods of manufacture where dies have been employed, such dies having been fashioned usually of such relative size that a drawing instead of a shearing action resulted.

According to one form of the invention the male portion of the die is made slightly larger than the recess in the female portion or counterpart.

30 The sides of the device upon the dies are made perfectly vertical with respect to the surface thereof and upon insertion of a metal plate of the required thickness and the application of sufficient pressure, the male portion of the die will force the metal

bodily against the female portion or counterpart.

Owing to the fact that the recess of the female portion is of lesser cross-sectional area than the projection of the male portion 55 of the die, there results a compression of the metal around the edges of the said recess.

This compression of the metal permits of the metal forming the raised portion of the device, which has already entered the recess of the female portion of the die, being pushed still further into the said recess.

In order to make the operation of the invention quite clear there will now be described, by way of example, the application 60 thereof to the production of a raised or embossed device upon a metal plate, reference being made to the accompanying drawing, in which:-

Figure 1 is a plan view of a portion of an 70 embossed metal plate produced by the method according to the invention,

Figure 2 is a section on the line 2-2 of Figure 1.

Figures 3 and 4 are diagrammatic sections 75 showing the male and female portions of one form of die at the commencement and at the close of the stamping operation respectively, and

Figures 5 and 6 are similar views showing 80 another form of die.

In order to produce an embossed device 1, on a metal plate 2, it is obvious that both the male and female portions of the die will need to be of the appropriate shape. Hence the 85 female portion 3 of the die is formed with a recess, part of which is indicated at 4 in Figures 3 and 4 of the size and shape of the device 1 to be embossed, whereas the projection of the male portion 5 of the die is formed of a similar shape but of slightly greater effective area than the said device 1. Part of the projection of the male portion of the die is indicated at 6 in Figures 3 and 4.

90 By making the sides 9 of the device upon the dies perfectly vertical with respect to the surface or plane of the work, the device whether embossed or intaglio will be formed 95 with perfectly vertical sides and the outlines 100

or edges at the angles will be perfectly sharp and such as would be produced by an ordinary engraving or milling machine.

When the metal plate 2 is inserted between the co-operating dies 3, 5, and sufficient pressure is applied thereto, it will be evident that the portion 7 of the metal plate registering with the recess 4 of the female portion 3 of the die will be forced or raised 10 into the said recess.

Furthermore, there will be a marginal portion 8 of metal connecting the embossed portion 7 with the plate 2 which will be compressed between the faces of the female portion 3 of the die and of the projection 6 of the male portion 5 thereof respectively, owing to the fact that the projection 6 is of larger effective area than the recess 4.

The effect of this compression is to cause 20 the said marginal portion of metal 8 to tend to expand laterally between the two die portions 3 and 5. Now the tendency towards lateral expansion is checked in the outward direction by the comparatively large portion 25 of the metal plate 2 surrounding the raised or embossed portion 7 thereof, whilst the tendency towards lateral expansion, possessed by the marginal portion 8 under compression, is unchecked in the inward direction 30 owing to the recess 4 in the female portion of the die.

Hence the raised portion 7 of the metal plate 2 is forced still further into the recess 4 by this tendency towards inward lateral expansion, but, as the lines at which the shearing action due to the dies takes place on opposite sides of the work do not coincide, there is no danger of severing the metal completely.

40 Obviously the projection 6 of the male portion of the die must be less in height than the thickness of the plate being treated otherwise that portion of the metal forming the device would be pushed completely through 45 and a perforation in the metal plate would result.

It will be understood that the process of manufacturing intaglio metal plates only differs from the above in that, in this case, 50 the projection of the male portion of the die is formed of the same size and contour as the device to be produced, the recess of the female portion of the die being of slightly smaller size than the same.

55 In a modification of the invention the recess of the female portion of the die is not formed of sufficient depth to allow of the metal being raised therein to the extent indicated above.

60 Hence the pressure applied to the die portions causes the male portion of the die to force the metal plate against the female portion and, as before, the portion of the plate 65 registering with the recess of the female

portion enters the same to form the raised device.

The marginal portion of the metal connecting the embossed or raised portion with the plate is compressed as before, but is unable to expand so that the said connection is consolidated and strengthened.

In a further modification of this invention, in order to produce embossed devices having rounded edges but the sides of which are vertical relatively to the metal plate, the projection of the male portion of the die is made of lesser effective area than the recess of the female portion of the die and of lesser depth than the same. Such an arrangement is illustrated in Figures 5 and 6 like parts being designated by the same reference numerals as in Figures 3 and 4.

70 The sides, as before, are vertically disposed relatively to the plate to be embossed and upon applying pressure to such a pair of co-operating die portions, the embossed device is produced with vertical sides merging into the raised surface of the device at the edges thereof.

75 The difference in the effective dimensions of the two parts of the die may be varied within limits according to the malleability of the metal plate, and in some cases this difference may be as small as $\frac{1}{2000}$ th of an inch. In the diagrams a substantial difference 80 in the effective dimensions of the two parts of the die is indicated for the sake of clearness.

85 The plates produced by the method and means forming the subject matter of this invention are applicable to various uses as, for example, signs, name-plates, number-plates, identification plates for vehicles, etc.

90 I claim:—

95 1. A method of manufacturing embossed or intaglio metal plates by means of a stamping operation comprising arranging a metal plate between male and female die portions of different effective areas, the side edges of the male and female portions being 100 perpendicular to the plane of the face of the work, and applying pressure to one of said die portions sufficient to cause the male portion of the die to push the metal registering therewith bodily with a semi-shearing action into the like female portion of the die, whereby either an embossed or an intaglio figure is formed upon the plate, the figure 105 having side edges perpendicular to the side edges of the plate such as would be produced in an ordinary engraving or milling machine.

110 2. In a method of manufacturing embossed or intaglio metal plates as claimed in 115 claim 1, the use of a die having male and female portions wherein the male portion has a larger effective area than the female portion or counterpart and the side edges 120 of the figure defined by each of the said 125

male and female portions are perpendicular to the plane of the work.

3. A method of manufacturing embossed or intaglio metal plates by stamping comprising disposing the metal plate between dies having male and female die portions and having different effective areas, the female die portion being less in depth than the thickness of the metal to be embossed and the male portion having a projection less in depth than the metal to be embossed, and applying pressure to one of said dies sufficient to bring the faces of the dies outward of the male and female portions into contact with the opposite faces of the work to thereby cause the material at the junction of the embossed portion with the body of the plate to be compressed to a greater degree than the remainder of the plate.
